STOCKING

Abe A. Bochner, Brooklyn, N. Y., and Herszel Zylberberg, Norristown, Pa.

Application May 17, 1950, Serial No. 10,005

Term of patent 14 years

(Cl. D47—7)

To all whom it may concern:

Be it known that we, Abe A. Bochner and Herszel Zylberberg, citizens of the United States and Poland, respectively, residing at Brooklyn, in the county of Kings and State of New York, and Norristown, in the county of Montgomery and State of Pennsylvania, respectively, have invented a new, original, and ornamental Design for a Stocking, of which the following is a specification, reference being had to the accompanying drawing, forming part thereof.

Fig. 1 is a side elevation of a stocking embodying our new design; and

Fig. 2 is a fragmental rear view thereof.

The top of the stocking is of a conventional plain design.

The dominant feature of the present design is particularly observable from Fig. 2. It comprises a substantially bottle-shaped formation with a relatively long, downwardly reducing head portion, a neck formation depending from the head portion and a body portion connected with the neck by an inwardly and outwardly curved

stepped line formation, which terminates in slanting, relatively long step-like intervals, from which depend gradually enlarging steps. From the last step the body reduces towards the vertical center line. The curved top end as well as both sides of the design are bordered by double lines, consisting of an interior thin line and an exterior heavier line.

We claim:

The ornamental design for a stocking, substantially as shown and described.

ABE A. BOCHNER.
HERSZEL ZYLBERBERG.
